AMPLIFIER

Masanori Hamada, Osaka, Japan, assignor to Matsushita
Electric Industrial Co., Ltd., Osaka, Japan

Filed Aug. 4, 1971, Ser. No. 169,151

Term of patent 14 years

Int. Cl. D14—03

U.S. Cl. D26—14 L

FIG. 1

FIG. 2

FIG. 1 is a top, right side, front perspective view of an amplifier incorporating my new design; and

FIG. 2 is a bottom, rear perspective view thereof, as seen from the opposite side of FIG. 1.

Portions of the drawing figures are shaded to indicate contrast in appearance, and portions are diagonally inclined to indicate transparency.

I claim:

The ornamental design for an amplifier, as shown and described.
